ASH TRAY OR SIMILAR ARTICLE

Frank J. Benes, Lancaster, Ohio, assignor to Anchor Hocking Glass Corporation, Lancaster, Ohio, a corporation of Delaware

Filed Oct. 20, 1964, Ser. No. 82,250

Term of patent 14 years

(Cl. D85—2)

FIG. 1 is a perspective view of an ash tray or similar article showing my new design;

FIG. 2 is a top plan view thereof;

FIG. 3 is a side elevational view thereof;

FIG. 4 is an end elevational view thereof; and

FIG. 5 is a sectional view taken along line 5—5 of FIG. 2.

The characteristic feature of the present invention resides in a peripheral rim along the upper edge of each side wall of the ash tray or similar article wherein each rim tapers from a relatively wide midsection which overhangs its dependent side wall to relatively narrow sections at each corner of the ash tray or similar article.

I claim:

The ornamental design for an ash tray or similar article, substantially as shown and described.
